AUTOMATIC RIBBON REVERSING MECHANISM FOR TYPEWRITERS

Marc Grandjean, Paris, France

Application September 11, 1928, Serial No. 305,299, and in France October 4, 1928

3 Claims. (Cl. 197—165)

I have filed an application in France Oct. 4, 1927.

The invention has for its object a device for automatically reversing the inking ribbon longitudinal motion in stenographic machines, said ribbon winding in a known way on two reels fitted on two hubs rigid with two worm wheels operated alternately by two worm wheels.

The invention essentially consists in that the reversal is obtained by means of a device actuated by a spring previously tensioned by pressing upon a knob and held in tensioned condition until it is released by the action of an abutment provided at each end of the ribbon, this spring engaging one of the worms with the respective toothed wheel and disengaging the other.

A form of carrying out the subject-matter of the invention is illustrated, by way of example, in the accompanying drawings, in which:

- 20 Fig. 1 is a top plan view.
- Fig. 2 is a rear view.
- Fig. 3 is an underside plan view.
- Fig. 4 a longitudinal section through the middle portion.
- 25 Figs. 5 to 7 diagrammatically illustrate the operation of the reversing device.

The device according to the invention is mounted on a frame 33 arranged in the casing of the machine. The ribbon-carrying spools 34 are, 30 as usual, fitted on hubs 34a provided with a key and rigid with worm wheels 34b loosely mounted on shafts 34c secured on the frame 33.

The rotation of the worm wheels 34b according to the direction of movement of the ribbon is 35 alternately controlled by worms 37 secured on the ends of a shaft 38 or in one piece with the latter. The shaft 38 can rotate in bearings 44 (Fig. 3) rigid with a frame 45 pivoted on a vertical shaft 46, on the lower side of the frame (Fig. 4). This 40 shaft 46 carries a slotted head 46a and is secured at the top in a member 46b secured on the frame 33. The frame 45 is guided, on the one hand, between the head 46a of the shaft 46 and the lower face of the frame 33 and, on the other hand, at 45 the free end of the frame, by a tongue 46c sliding between the lower face of the frame and a guide 47 secured on this frame. The arrangement is such that, by oscillation of the frame 45 towards the right or towards the left, one or the other of 50 the worms engages with the corresponding worm wheel.

Between the bearings 44 of the frame, the shaft 38 carries a pawl and ratchet device connected to the universal bar of the machine, so that upon 55 each depression of the keys the shaft carrying the

worms 37 rotates through a fraction of a revolution. As one or the other of the worms is always in engagement with the corresponding wheel 34b, the latter as well as its ribbon-carrying spool 34 must follow the intermittent rotation of the shaft 60 38 and the ribbon itself is moved forward, as in all typewriting machines.

The above pawl and ratchet device is composed (Figs. 3 and 4) of a plate 39 loosely mounted on a hub 38a rigid with the shaft 38. The connection between the plate and the hub in one direction only is obtained by pawls 40 mounted on the plate and engaging with the teeth of a ratchet 42 under the action of springs 41. The plate 39 is connected to the universal bar of 70 the machine by a system of levers and links 43 partially illustrated.

According to the invention, the reversal of the movement of the inking ribbon must be obtained by an automatic oscillation of the frame 45 when the ribbon has entirely unwound in one direction or the other. By automatic operation, the inventor means that the operator presses upon a knob immediately after reversal, or in any case, before the end of the unwinding of the ribbon 80 in the new direction, and thus sets the reversing device which is held in a stretched condition until the ribbon has entirely unwound. As soon as the ribbon comes to its end, the reversing device is released by the action of an abutment and 85 causes the frame 45 to rock, so that the worm 37 which was free up to this moment, engages with the teeth of the corresponding wheel 34b.

In the drawings, the knob which is to be pressed upon by the operator is indicated at 51. 90 It can slide and rotate in a fixed guide 51b mounted on the member 46b. On the side of this member, the guide has two inclines 51c, (Figs. 4 and 7) forming an angle the apex of which is downwardly directed and is exactly situated 95 in the axis of the machine. On the opposite side, the guide 51b is obliquely cut at its lower end, and, at this place, a circular groove 51d is provided about the knob 51. The latter is moreover extended downwardly in a tail piece 51e 100 against which bears a spring 52 secured to the frame 33 and tending to cause the knob to rise when the latter has been pressed upon by the operator.

But the knob is held in its lowered position by 105 a pawl and ratchet device, constituted for instance by a rod 53 which enters the groove 51d and remains therein until the device is tripped at the end of the unwinding of the ribbon.

The knob 51 carries a claw 51a which projects 110

laterally and is returned exactly in the median plane of the machine by one of the inclines 51c when the operator presses upon the knob, but, when the knob rises under the action of the spring 52, this claw engages with a reversing member 50, rocking on a stud 50a and in which is provided a heart-shaped recess, so that for successive rising movements of the knob under the action of the spring 52, this reversing member alternately rocks in two opposite directions. This reversing member, provided with a point at its upper part, is held in each position by a spring 60, having a V-shaped section, secured on the upper side of the member 46b and cooperating with the point of the reversing member. The latter has, at its lower end, a fork piece 49, between the branches of which extends a resilient tongue secured on the rocking frame 45. The rocking movement of the reversing member 50, produced under the action of the spring 52 through the medium of the knob 51 and of the claw 51a, is therefore transmitted, by the said tongue 48, to the frame 45 and, by the latter, to the worms.

25 The reversing device comprising the knob 51, the fixed inclines 51c and the reversing member 50 cooperating with the spring 60. Its operation has been diagrammatically illustrated in Figs. 5, 6 and 7. These figures only show the essential parts, seen from the inner side of the machine (from the left in Fig. 4). The path followed by the claw 51a is indicated by small arrows.

In Fig. 5, it has been assumed that the operator has previously pressed upon the knob 51 and has, from this fact, tensioned the spring 52. The claw 51a has therefore been moved to the bottom of the angle formed by the inclines 51c, that is to say in the position I.

As soon as the knob 51 is released by the rod 58 and that the spring 52 causes it to rise, the claw is successively moved to the positions II, III and IV (Figs. 5 and 6). The upper point of the reversing member 50 (Fig. 5) is located to the left of the spring 60, so that the point 50b of the heart-shaped recess is located to the right of the vertical axis of the machine.

In the position II, the claw therefore strikes against the lefthand side of the point 50b and slides on this side to the bottom of the left-hand notch towards the position III, this of course having for effect to cause the knob 51 to rotate about its axis. When passing from position III to position IV, the claw 51a produces the oscillation of the reversing member on its stud 50a in the direction of the arrow, and the upper point of the reversing member passes from the left-hand side to the right-hand side of the spring 60, and the inner point 50b passes from right to left (Fig. 6). But, from this fact, the tongue 48 extending between the branches of the fork piece 49, is also moved, the frame 45 pivots about its shaft 46, and the direction of movement of the ribbon is thus reversed.

All the parts of the reversing device remain in this position until the operator again tensions the spring 52 by pressing upon the knob 51. The claw 51a therefore first moves to the position V (Fig. 6) and slides on one of the inclines 51c which returns it to the initial position VI by causing the knob 51 to rotate. The claw remains in this position until the reversing device is again released at the end of the unwinding of the ribbon. The knob rises under the action of the spring 52, so that the claw 51a first comes to the position VII, strikes against the right-hand side

of the point 50b, slides on this side towards the position VIII to the bottom of the right-hand notch and passes to the position IX (Fig. 7) by causing the reversing member to rock. During this time, the upper point of the reversing member again moves to the left-hand side, and the inner point 50b, as well as the fork piece 49 with the tongue 48, moves again to the right-hand side.

When the spring 52 is again tensioned, the claw 51a will first move to the position X and will slide on the incline 51c which will return it to the position I.

The device serving to actuate the tripping rod 58 can be of any type. As shown in Fig. 4, this rod constitutes an element of a parallel motion 53, 54, 57, the side 54 of which is rigid with the shaft 55. A spring 58a tends to push the rod in the circular groove of the knob.

The shaft 55 carries, at each end, a lever 56, which is located in the path of an abutment 59 provided at each end of the inking ribbon. When the unwinding of the ribbon is at its end, this abutment engages with the corresponding lever 56 and causes it to rock. Through the medium of the parallel motion 53, 54, 57, the rod 58 is then removed from the groove of the knob and the latter rises under the action of the spring 52.

I claim:

1. In a device for automatically reversing the inking ribbon longitudinal motion in stenographic machines, the combination of two reels upon which the said ribbon winds itself, two hubs on which are fitted the reels, two worm wheels rigid with said hubs, two worm drives adapted to operate alternatively the said worm wheels, reversing means for putting out of mesh or engagement with one of the worm wheels one of the said drives and for putting into engagement with the other worm wheel the other drive, a spring adapted to operate the said reversing means, a controlling plunger pressed by the operator in order to tension the said spring, gearing means adapted to maintain the said spring in the tensioned state and abutments provided at the ends of the inking ribbon of the machine, the said abutments being adapted to act upon the said reversal means when the ribbon is almost entirely wound off.

2. In a device for automatically reversing the inking ribbon longitudinal motion of stenographic machines, the combination of two reels upon which the said ribbon winds itself, two hubs on which are fitted the reels, two worm wheels rigid with said hubs, two worm drives adapted to operate alternatively the said worm wheels, a shaft carrying at each of its ends one of the said worms, a frame carrying the said shaft and adapted to oscillate transversely towards the right and towards the left, reversing means adapted to cause the said frame to rock in the right or left direction, alternatively, a spring adapted to actuate the said reversing means, a plunger pressed by the operator in order to tension the said spring, means adapted to maintain the said spring in tensioned position, and abutments provided at the ends of the inking ribbon of the machine, the said abutments being adapted to act upon the said reversing means when the ribbon is almost completely wound off.

3. In a device for automatically reversing the inking ribbon longitudinal motion in stenographic machines, the combination of two reels upon which the said ribbon winds itself, two hubs on which are fitted the reels, two worm

wheels rigid with said hubs, two worm drives adapted to operate alternately the said worm wheels, a shaft carrying at each end one of the said worms, a frame carrying the said shaft and 5 adapted to rock transversely to the right or to the left so that one or the other of the worm drives alternatively engage one of the worm wheels, a reversing device provided with a recess in the form of a heart and an external point, a 10 horizontal spindle on which the said reversing means rocks, a spring for laterally repelling the upper point of the said reversing means, a fork piece on the said reversing means, a tongue secured to the said frame and so arranged as to 15 enter between the branches of the said fork, a

driving spring adapted to actuate the said reversing means for causing the said frame to rock and for putting one of the worm drives into engagement with one of the worm wheels and the other worm drive out of engagement with the other worm wheel, a plunger pressed by the operator in order to tension the said driving spring, means adapted to maintain the said spring in tensioned position, and abutments disposed at the ends of the inking ribbon of the machine, said abutments being adapted to act upon the said means when the ribbon is almost entirely wound off.

MARC GRANDJEAN.
